INVENTOR,

Henry Callsen,

BY

James P. Dahmen

ATTORNEY.

UNITED STATES PATENT OFFICE.

HENRY CALLSEN, OF BROOKLYN, NEW YORK.

DENTAL BRIDGE.

1,323,743.

Specification of Letters Patent. Patented Dec. 2, 1919.

Application filed August 23, 1919. Serial No. 319,408.

To all whom it may concern:

Be it known that I, HENRY CALLSEN, a citizen of the United States, residing at Brooklyn, Kings county, and New York State, have invented certain new and useful Improvements in Dental Bridges, of which the following is a specification.

This invention relates to dental bridges and its object is to anchor the bridge at each end in adjacent teeth by embedding a part of the improved device in each tooth, securing the same by means of a metal inlay or attaching the same by means of a crown and it consists of a female member consisting of a socket secured to the tooth as above described and a male member, comprising a resilient wedge, and a stem to be secured to the bridge work and which affords a simple means for inserting or removing the latter for cleaning or to repair the bridge.

These and other objects and details of the invention are more fully described in the following specification, set forth in the appended claims and illustrated in the accompanying drawings, wherein:

Figure 1 is a sectional view of a tooth showing the location of the anchorage on the female member,

Fig. 2 is a perspective view of the female socket,

Fig. 3 is a perspective view of the wedge or male member,

Fig. 4 is a vertical sectional view of a modified form of the socket,

Fig. 5 is a side view of the wedge,

Fig. 6 is a plan view.

For sanitary purposes, it is found very necessary that bridge work carrying several teeth and located on sound teeth should be removable so that they may be easily cleansed and sterilized. In addition to this feature a removable bridge affords excellent opportunities for producing a perfect piece of work or properly repairing the same if damaged or worn.

In the present invention, the female or socket member 10, consists of a sheet metal frame open at the front and top and having the straight back 11, side wings 12 and sloping bottom 13, the whole being inserted in a correspondingly made cavity in the tooth and cemented therein to form a lining.

It will be observed in Fig. 1 that by forming the cavity with the sloping rear lower

end, no danger results of a near approach to the nerve 15, so that the sound tooth is in no way injured nor jeopardized.

The male member or wedge 16 is adapted to form one end of the bridge and is attached to the same by means of the stem 17 in any desired manner, and the member is of a shape to correspond with the interior of the socket 10 in which it fits as shown in Fig. 6, the beveled sides fitting against the wings 12, so that it may not be pulled out when inserted, and at the rear of the member is a spring 18, normally a short distance from the rear face of the member and soldered or riveted at its lower corner.

When the male member is inserted by means of its reduced lower end and forced downward, the spring 18 bears against the back 11 of the socket member and creates a certain amount of friction as the wedge is shoved home and by the time the two parts are completely fitted, they are firmly secured together.

When it is desired to remove the bridge the upward pull of the same will overcome the pressure of the spring 18 and the male members at each end of the bridge will readily yield.

In the modified form shown in Figs. 4 and 5 a certain amount of space is left between the spring 20 and the member 21 on account of the two not corresponding in shape on that face and consequently, the friction of the spring does not take place until the wedge has reached the bottom of the socket, when it holds the two parts firmly together. The socket corresponds with the lower corner 22 of the male member and the spring is consequently compressed and the friction results therefrom.

Besides providing for a safe socket and non-interference by the inclined bottom 13, it affords a quick and ready means for cleaning the same when the bridge is removed, so that no dangerous germs may find lodgment about the device.

It is evident that the parts may be otherwise arranged or modified without departing from the essential features above described or from the scope of the appended claims.

What I claim as new is:

1. In a dental bridge, the combination of a socket member attached to a tooth, and a

resilient wedge exerting an outward pressure adapted to be secured in the socket member and to carry a bridge.

2. In a dental bridge, the combination of 5 a socket member adapted to be attached to a tooth, a wedge member adapted to be fitted in the socket and carry one end of the bridge and exert a longitudinal pressure thereon, and friction means securing the wedge in the 10 socket.

3. In a dental bridge, the combination of 15 a metal socket member fitted in a tooth, a wedge member with a stem at its lower end to carry the bridge and a spring secured to 20 the wedge and adapted to create friction with the socket member.

4. In a dental bridge, the combination of 25 a socket member having a sloping bottom and an open top and front, a wedge member having means for carrying a bridge, and a spring to create friction between the wedge and the socket members and force the wedge 30 and bridge outward.

5. In a dental bridge, the combination of 35 a socket member having a sloping lower side and open at the top and the front wings at the front opening, a wedge member having a stem and adapted not to interfere with the adjacent tooth, and a spring adapted to force 40 the wedge member against the wings.

6. In a dental bridge, the combination of 45 a sheet metal member adapted to form the lining for a socket in a tooth, a wedge member adapted to fit in the sheet metal member, and a flat spring secured to the latter parallel with its rear face and extending slightly beyond same.

7. In a dental bridge, the combination of 50 a sheet metal lining adapted to fit the socket in a tooth, a wedge member adapted to carry 40 a bridge, a stem for the bridge and depending from the wedge and below the teeth on the said bridge, and a spring secured to the lower side of the wedge, parallel with its rear face and extending beyond the wedge at its 45 lower rear corner.

8. In a dental bridge, the combination of 55 a tooth having a socket, a wedge having resilient frictional means on its inner face and adapted to force it outward, and a stem depending from the lower end of the wedge and adapted to extend below the adjoining bridge and its teeth.

In testimony whereof, I have signed my name to this specification in the presence of 55 two subscribing witnesses this August 1919.

HENRY CALLSEN.
